Patented Oct. 21, 1919.

THE COLUMBIA PIANOGRAPH CO. WASHINGTON, D. C.

UNITED STATES PATENT OFFICE.

HENRY JAMES COLLIS, OF TAUNTON, MASSACHUSETTS.

SKATE-STRAP.

1,319,269.

Specification of Letters Patent.

Patented Oct. 21, 1919.

Application filed January 6, 1917. Serial No. 140,897.

To all whom it may concern:

Be it known that I, HENRY JAMES COLLIS, a citizen of the United States, and resident of Taunton, in the county of Bristol and 5 State of Massachusetts, have invented certain new and useful Improvements in Skate-Straps, of which the following is a specification.

This invention relates to skate straps, and 10 it has for its object to provide a device of this character which will afford maximum comfort to the wearer, which will be exceedingly simple and inexpensive in construction, and which will furthermore possess 15 advantages in point of effectiveness, convenience and general efficiency.

My invention has special relation to skate straps which provide a cushion pad extending across the instep to take up or compensate 20 for and relieve the pressure of the strap when it is tightened and secured in operative position.

In the drawings—

Figure 1 is a top or plan view of my improved 25 skate strap device.

Fig. 2 is an edge view thereof in its operative position.

Fig. 3 is a detail longitudinal sectional view on the line $x-x$, Fig. 1.

30 Fig. 4 is a detail transverse sectional view on the line $y-y$, Fig. 1.

Fig. 5 is a top or plan view illustrating a modified construction.

Fig. 6 is a detail transverse sectional view 35 on the line $z-z$, Fig. 5.

Corresponding parts in all the figures are denoted by the same reference characters.

Referring to the drawings, 1 designates the pad body member, which constitutes the 40 main portion or body of the device and is of elongated shape affording sufficient length to extend over and across the instep where the strap passes across the same and of sufficient width to afford a cushion which will 45 take up or compensate for and relieve the pressure of the skate strap when it is secured across the instep. The pad body member may be of any suitable contour in its elongated extent and is flexible or pliable, 50 affording a soft body member conforming to the instep. The body member 1 is constituted in its entirety by strips of leather or other suitable pliable material and a pad surface carried thereby. In general construction 55 said pliable body comprises a main sheet, 2,

corresponding to the longitudinal and transverse extent of the body member and carrying at its under surface a pad, 3, which is preferably constituted by a sheet of soft wool corresponding in extent to the surface 60 dimensions of the main sheet 2, and at the outer or top surface of the main sheet is carried a supplementary sheet, 4, which forms a tubular body construction through which the strap passes. The pad 3 may be 65 secured to the main sheet 2 in any suitable manner, for instance, adhesively, and the soft wool may be directly carried by the under surface of the main sheet or carried by a pliable base sheet, 5, which is secured to 70 the under surface of the main sheet. The supplementary pliable top sheet 4 preferably extends continuously and longitudinally of the base sheet 2 so that a continuous tubular passage, as at 6, extends longitudinally of the pad body member between 75 said supplementary sheet and main sheet, and the supplementary sheet is secured to the main sheet in its tubular relation thereto in any suitable manner, preferably by stitching. 80

In the preferred construction, the three elements of the pliable pad body member, the main sheet and the supplementary top sheet and the pad, are secured together by a 85 single stitching extending at and through the longitudinal edges of the three elements, as at 7, thus leaving the ends of the tubular construction produced by the main sheet and the supplementary top sheet open at the 90 terminal ends of said supplementary top sheet, as at 8.

The pad body member is carried by a securing strap, 9, which consists of a pliable strip of textile material, or leather having 95 suitable fastening means, as at 10, at its respective ends. The strap passes continuously through the continuous tubular construction formed by the supplementary top sheet 4 and the main sheet 2 at the top of 100 the pad body member, and is thus retained in connection with the latter throughout the longitudinal extent thereof and rests across the full longitudinal area of the pad and also across the main transverse area thereof. 105

In practice, the pad body member rests across the instep from side to side and extends over the area of the instep vertically to an extent corresponding to the width of the pad, and the securing strap or strip 9, 110

which projects at opposite ends of the continuous tubular construction by which it is carried in connection with the pad body member, is passed around under the foot 5 beneath the skate and is secured in tightened position by the fastening means at its terminal ends.

In Figs. 5 and 6 I have illustrated a modified construction in which the pad body 10 member 1 is provided with an additional top strip, 12, likewise of flexible material, extending across the supplementary top sheet 4 preferably at the central portion thereof. This additional top strip is relatively narrow 15 in its longitudinal extent and is secured at its side edges in connection with the body member, preferably by the same single stitching 7 by which the other three elements of the body member are secured together. This additional top strip element 20 affords a supplementary tubular construction constituting a passage, as at 14, in the longitudinal plane of the body member and between the top strip 12 and the top sheet 4, 25 through which the strap 9 may be passed in its connection with the pad body member, and which will especially serve to retain the free end of the strap after the latter is secured in fastened operative position, as 30 shown in Fig. 6.

The operation and advantages of my invention will be readily understood. The pad body member is soft and pliable in all its elements and extends as a soft cushion 35 over the area of the instep across which the securing strap passes. The pliable pad body member thus conforms to the curvature of the instep both transversely and vertically and serves to effectively protect the instep 40 against the pressure of the securing strap, the conditions being such that the pliable conforming pad body member underlies the longitudinal extension of the strap at all points where the latter is active in exerting 45 a pressure against the instep. The retention of the securing strap longitudinally, by the continuous tubular construction, in its connection with the pad body member effectively serves to preclude any slipping 50 or disarrangement of the pliable pad device and is also operative to prevent any tendency of the strap to vary its secured position. The device is exceedingly simple and inexpensive in construction, and by reason of 55 the structural characteristics of the pad body

member as herein described it may be economically constructed of small pieces or waste strips of pliable material.

Having thus described my invention, I claim and desire to secure by Letters Pat- 60 ent:

1. An improved cushion skate strap having a pliable body member adapted to extend across and conform to the instep and consisting of a main body strip carrying at 65 its under surface a soft and pliable pad cushion, a top body strip conforming to said main strip and extending longitudinally over the surface thereof, said main and top body strips being secured together only at their 70 longitudinal side edges leaving disconnected end edges and said strips thus conjointly forming a body member which is tubular throughout its longitudinal extent and open at both its ends, and a securing strap having 75 its body length passing longitudinally through said tubular body member and inclosed thereby beneath said longitudinal top strip and thus retained between and in bearing contact with said main and top body 80 strips throughout the longitudinal extent of the tubular body member.

2. An improved skate strap device, comprising a pad body member pliable in its entirety and adapted to extend across the instep and conform to the curvature thereof, 85 said pliable body member consisting of a main sheet carrying at its under surface a soft and pliable pad forming a cushion and at its outer or top surface a supplementary sheet conforming to the under main sheet and forming a tubular body construction extending longitudinally of the body member and an additional top strip or sheet 90 extending across the supplementary top sheet and relatively narrow in its longitudinal extent and forming a supplementary tubular construction between said top strip and supplementary sheet, and a pliable securing strap carrying said pad body member 95 and passing continuously through the tubular body between the under main sheet and the supplementary top sheet which covers the same and adapted to also pass through the supplementary tubular construction 100 formed by said additional top strip.

In testimony whereof I have signed the foregoing specification.

HENRY JAMES COLLIS.
